UNITED STATES PATENT OFFICE

JONATHAN C. STIMSON, OF CHICAGO, ILLINOIS

DESIGN FOR AN AUTOMOBILE SIGNAL LAMP

Application filed April 23, 1932. Serial No. 43,585. Term of patent 7 years.

To all whom it may concern:

Be it known that I, JONATHAN C. STIMSON, a citizen of the United States, residing at the city of Chicago, in the county of Cook and State of Illinois, have invented a new, original, and ornamental Design for an Automobile Signal Lamp, of which the following is a specification, reference being had to the accompanying drawing, forming part thereof and in which:

The signal lamp comprises a lamp casting as shown, having a cover glass which is figured on the back to provide a reflector for external light, a conventional figuring being indicated in broken lines.

I claim:

The ornamental design for an automobile signal lamp substantially as shown and described.

In testimony whereof I affix my signature this 20th day of April, 1932.

JONATHAN C. STIMSON.
